UNITED STATES PATENT OFFICE.

AMBROSE H. WHITE, OF BROOKLYN, NEW YORK, ASSIGNOR TO INTERNATIONAL PAPER COMPANY, A CORPORATION OF NEW YORK.

TEST-VALVE MECHANISM FOR DRYING-CYLINDERS.

1,251,602.

Specification of Letters Patent.

Patented Jan. 1, 1918.

Application filed July 17, 1916. Serial No. 109,825.

To all whom it may concern:

Be it known that I, AMBROSE H. WHITE, a citizen of the United States, residing at Brooklyn, in the county of Kings and State 5 of New York, have invented certain new and useful Improvements in Test-Valve Mechanism for Drying-Cylinders, of which the following is a specification, reference being had therein to the accompanying drawing.

10 In drying apparatus, designed more particularly for drying paper in paper making machines, hollow steam heated rotary cylinders are employed, around which the paper web passes, the heating steam being introduced, usually under pressure, through hollow journals on the cylinders. Such cylinders are usually equipped with means for the continuous discharge of the water of 15 condensation collecting in the lower portion of the cylinder, since any considerable accumulation of water therein will greatly impair the heating effect of the steam. It is desirable therefore that means be provided 20 to enable the attendant to ascertain if the water is being properly discharged from the cylinder or has collected therein, and if so to what extent.

My invention aims to provide inexpensive 30 means of simple construction for this purpose, and the invention consists in a test valve of improved form and construction applied to a vent opening in the cylinder, preferably in the end thereof, the said valve being provided with an actuating member 35 adapted in the rotation of the cylinder to engage with an abutment, such for instance as an implement, tool or similar object, held fixedly in the hands of the attendant in the path of the actuating member, such engagement 40 causing the actuating member to be moved and the valve to be opened or closed. By the employment of such valve, the attendant may from time to time actuate the 45 same for testing purposes; the character of the jet issuing through the vent opening, whether steam or water, and the point in the rotation of the cylinder where the jet changes from water to steam, will reveal 50 to the attendant the conditions within the cylinder, both as respects the absence or presence of water, and the level of the accumulated water. The form, arrangement 55 and construction of the parts is such that the valve may be actuated in the manner de-

scribed, while the cylinder is rotating at a high rate of speed, so that a test may be performed without reducing the speed or without interfering with the normal operation thereof.

60 In the accompanying drawings:

Figure 1 is an elevation partly in section of a drying cylinder having my improved test valve applied thereto.

Fig. 2 is a section on an enlarged scale 65 through the end portion of the cylinder and the test valve.

Fig. 3 is an end elevation showing the form of the valve actuating member.

Fig. 4 is an end view of the valve body.

Fig. 5 is a sectional view on an enlarged scale through the end of a drying cylinder, having a test valve applied thereto embodying my invention in a modified form.

Fig. 6 is an inside face view of the actuating member showing the valve actuating cams thereon.

Fig. 7 is a perspective view of a portion of the cylinder showing how the valve actuating member is operated while the cylinder is rotating.

Referring to the drawings:

Referring to Figs. 1 to 4 inclusive, 1 represents one of a series of rotary hollow drying cylinders such as are employed in paper making machines for drying the damp paper web, around which cylinders the web is adapted to pass as the cylinders are rotated. The cylinders are heated internally by the introduction of steam thereto through a hollow journal 2, the water of condensation being continuously discharged from the cylinder by suitable means, in the present instance by means of the siphon pipe 3 passing through the hollow journal and terminating at its lower end adjacent the lower portion of the cylinder.

90 My improved test valve is applied to the head of the cylinder adjacent its periphery, and controls a vent opening 4 leading from the interior of the cylinder. This valve in the particular form of the invention shown in Figs. 1 to 4 comprises a valve seat 5 in the form of a disk seated in a bushing 6 screwed in an opening in the head of the cylinder. The disk is provided on its outer face with a concaved valve seat proper 7, a port 9 extending in an axial direction through the disk and having its inner end 95 in communication with the vent opening. 100 105 110

Mounted to turn in the bushing 6 on an axis parallel with the axis of rotation of the cylinder is a cylindrical valve body 10, the inner end of which is formed with a convex surface 11 seated against and adapted to co-operate with the concaved valve seat 7. A port 12 extends longitudinally through the valve body from end to end and communicates at its inner end with the end of a branch port 13 formed in the convex end of the body and extending circumferentially thereof part way around, in such position that it may be moved into and out of register with the port 9 in the valve seat 7. When the valve body is in such position that the circumferential port therein registers with the port 9, a communication will be established between the interior of the drying cylinder and the outside, through the vent opening, the port 9 and the ports 12 and 13. When, however, the valve body is turned on its axis so as to carry the circumferential port out of register with the port 9 as shown in Fig. 2, the vent passage will be cut off from communication with the outside. The valve body is turned by means of an actuating member 14 in the form of a flat plate fixed to the outer projecting end of the valve body and provided with a plurality of radially extending arms 15, four in the present instance, which are spaced equal distances from each other. The actuating member is adapted to be operated so as to operate the valve while the cylinder is rotating, its actuation being effected by interposing in the path of the actuating arms a suitable abutment 16 such as a hammer handle, tool, a stick or like implement, held fixedly in the hands of the attendant. The cylinder in its rotation will carry the arm of the actuating member into engagement with the abutment and by its continued movement will cause the actuating member to be shifted around a partial rotation and will correspondingly shift the valve body, this action bringing the next arm in position to be actuated in a like manner in the next rotation of the cylinder. It is seen therefore that in this manner the valve body may be shifted around intermittently on its seat and the valve successively opened and closed to correspondingly open and close the vent passage. In the operation of the valve to ascertain the presence or absence of accumulated water within the cylinder, and assuming that the valve is closed as shown in Fig. 2, the attendant interposes a suitable implement in the path of one of the upright arms of the actuating member, and the motion of the cylinder will engage the arm with the implement and cause the valve to be turned to open position. If there is accumulated water within the cylinder water will be dis-

charged through the valve as the inner end of the vent opening passes through the body of water and as the continued motion of the cylinder will carry the vent opening above the level of the water, the discharge of the water through the valve will cease and steam will issue. By permitting the cylinder to make a number of rotations with the valve in open position, and by noting the point in the rotation of the cylinder where the water ceases to flow and the steam begins to flow, the attendant will be enabled to calculate with sufficient exactness the level of the accumulated water within the cylinder. When this has been determined the obstructing implement is again placed in the path of the next arm of the actuating member, which by the first movement of the actuating member had been brought to position, and this arm being engaged with the implement the valve is given a further turn, and the ports being moved out of register, the valve will be closed and the communication through the vent opening cut off. If in the above described testing operations no water issues from the valve but only steam, the attendant will know of course that the cylinder contains no accumulated water.

In Fig. 5 I have illustrated a modification of my invention. Here it will be seen that the actuating member 14^a is rotatably mounted on a stud 17 projecting outwardly from the cylinder head alongside the valve, which latter is movable axially of the cylinder to open and closed positions and is operated by circumferential cams 14^b on the inner face of the actuating member. The valve seat 7^a in this case is formed on an annular rib projecting inwardly from the inner side of the bushing 6^a, which bushing contains an opening 6^b therethrough from end to end, the inner end of the opening being in communication with the vent opening 4^a and the outer end of the opening being in communication with the atmosphere. The valve body 11^a is of disk-like or circular form to co-operate with the valve seat, and is provided on its outer side with an outwardly extending axial actuating stem 11^b sliding through and guided in a guide opening in a spider 18 seated in the outer end of the bushing. At its inner side the valve body is provided with an inwardly extending axial stem 11^c sliding through and guided in an opening in a spider 19 at the inner end of the bushing, a spiral spring 20 encircling the stem 11^c and bearing respectively against the spider and valve body and acting to urge the valve body with spring pressure toward the seat to closed position. The outer stem 11^b projects beyond the end of the bushing in the path of the cams 14^b before alluded to, so that in the rotation of the actuating member 14^a the stem will be pushed inwardly by the cams against the force of the spring and will

move the valve body away from its seat and open the valve. There are two cams 14^b on the actuating member extending circumferentially thereof, each cam extending half way around, and each being formed with a high or elevated end 14^c which inclines gradually as at 14^d, and merges into a flat lower portion 14^e which terminates where the elevated portion of the other cam begins. 5 When the lower part of the cam is opposite to and engaged with the valve stem, the valve will be held in closed position by its spring. When now the actuating member 10 is turned by engagement with a suitable abutment or implement as hereinbefore described, the inclined face of the cam being carried past the end of the stem, will gradually force the stem inwardly and open the valve against the counter-pressure of the 15 spring. The parts are of such form and relative arrangement that the high part of the cam will be engaged with the valve stem at the moment that the actuating member disengages from the abutment or implement 20 and comes to rest, the result being that the valve will be retained in open position. The valve is allowed to remain in this position until the attendant by observing the nature 25 of the jet issuing through the valve, determines the conditions obtaining within the cylinder as heretofore described in connection with the first form of the apparatus. When this has been determined the valve 30 may be closed by again interposing the implement in the path of the next arm of the actuating member, which member will be caused to advance a farther distance and will thereby carry the high part of the cam 35 out of engagement with the valve stem and present the low part of the next cam opposite 40 the stem, the valve being quickly closed by the spring as the high part of the cam is disengaged therefrom.

It is seen therefore that the valve may be alternately opened and closed by the successive movements of the actuating member while the cylinder is rotating at high speed, it being unnecessary to slow down the cylinder or interrupt the operation of the machine in operating the valve to make the test. 50

The actuating member, it will be observed, extends in a plane parallel with the plane of the end of the cylinder and rotates about an axis parallel with the axis of rotation. 55 This arrangement I deem of importance and advantage in that it disposes the actuating member in such position relative to the end of the cylinder and the direction of rotation, that the operating abutment or implement 60 may be interposed with precision and certainty in the path of the arms of the actuating member, notwithstanding the fact that the cylinder may be rotated at high speeds. 65 The valve may therefore be accurately and effectively controlled in its opening and clos-

ing movements, and the tests performed with celerity and uniformity.

The construction as a whole is very simple in its make-up, direct in its action and may be produced and applied to the drying cylinder at a minimum of expense. 70

In the foregoing description and accompanying drawings I have disclosed my invention in the particular forms which at the present time I have found satisfactory for 75 the ends to be attained. It is manifest, however, that the details of the mechanisms may be variously changed and modified without departing from the spirit of my invention provided the operation will be substantially 80 as indicated above; and it will be understood that the invention is not limited to any particular form or construction of the parts except in so far as such limitations are specified in the claims. 85

Having thus described my invention, what I claim is:

1. In combination with a rotary cylinder having means for the introduction of steam thereinto and provided with a vent opening, 90 a valve applied to said opening, and a rotary valve actuating member sustained by the cylinder and provided with a plurality of actuating arms adapted in the successive rotations of the cylinder to be engaged successively with an abutment to actuate the valve, said arms being disposed at such intervals that the movement of one arm by engagement with the abutment in one rotation of the cylinder will bring another arm 95 in position for actuation. 100

2. In combination with a rotary cylinder having means for the introduction of steam thereinto and provided with a vent opening, a valve applied to said opening, and a valve 105 actuating member sustained by the cylinder and rotatable relatively thereto about an axis parallel or substantially so with the axis of rotation of the cylinder, said actuating member being adapted by the rotation 110 of the cylinder to be engaged with an abutment and moved relatively to actuate the valve.

3. In combination with a rotary cylinder having means for the introduction of steam 115 thereinto and provided with a vent opening, a valve applied to said opening, and a valve actuating member comprising a rotary star wheel sustained by the cylinder and adapted by the rotation of the cylinder to be engaged 120 with an abutment and moved relatively to actuate the valve.

4. In combination with a rotary cylinder having means for the introduction of steam thereinto and provided with a vent opening, 125 a valve applied to said opening, and a rotary valve actuating member sustained by the cylinder and provided with four radially extending arms spaced equal distances apart, said arms adapted in the successive rotations 130

of the cylinder to be successively engaged with a relatively fixed abutment to actuate the valve.

5. In combination with a rotary cylinder having means for the introduction of steam thereinto and provided with a vent opening, a valve seat having a port communicating with the vent opening, a valve body rotatable on said seat and provided with a port 10 adapted in the rotation of the valve to be moved into and out of register with the port in the valve seat, said valve being rotatable about an axis parallel or substantially so with the axis of rotation of the cylinder, and 15 an actuating member fixed to the valve and adapted by the rotation of the cylinder to be engaged with an abutment and moved relatively to actuate the valve.
6. In combination with a cylinder having means for the introduction of steam thereinto and provided in one end with a vent opening, a valve applied to said opening, and a valve actuating member extending at the outer side of the end of the cylinder and parallel 25 therewith and rotatable about an axis parallel or substantially so with the axis of ro-

tation of the cylinder, said member adapted by the rotation of the cylinder to be engaged with an abutment and moved relatively to actuate the valve.

80

7. In combination with a rotary cylinder having means for the introduction of steam thereinto and provided with a vent opening, a valve applied to said opening, and a valve actuating member sustained by the cylinder 35 and adapted to be moved relatively thereto to actuate the valve without slowing down the speed of the cylinder.

8. In combination with a rotary cylinder having means for the introduction of steam 40 thereinto and provided with a vent opening, a valve applied to said opening, and a valve actuating member sustained by the cylinder and rotatable relatively thereto, said actuating member being adapted by the rotation 45 of the cylinder to be engaged with an abutment and moved relatively to actuate the valve.

In testimony whereof, I have affixed my signature.

AMBROSE H. WHITE.
